UNITED STATES PATENT OFFICE.

CHARLES CARLETON, OF CHICAGO, ILLINOIS, ASSIGNOR OF ONE HALF TO
E. M. HULSE, OF SAME PLACE.

SPRING BED-BOTTOM.

SPECIFICATION forming part of Letters Patent No. 349,478, dated September 21, 1886.

Application filed July 3, 1886. Serial No. 207,024. (No model.)

To all whom it may concern:

Be it known that I, CHARLES CARLETON, a citizen of the United States, and a resident of Chicago, county of Cook, and State of Illinois, 5 have invented new and useful Improvements in Spring Bed-Bottoms, of which the following is a specification, reference being had to the accompanying drawings, illustrating the invention, in which—

10 Figure I is a vertical longitudinal sectional elevation of a spring bed-bottom embodying my invention, the coil-springs being represented as supported directly on suspending-wires. Fig. II is the same view as Fig. I, except conical springs are shown as supported by transverse slats interposed between the suspending-wires and springs. Fig. III is an inverted view of the form of spring bed-bottom shown at Fig. I. Fig. IV is a section of the 20 edge of a coiled-wire woven mattress, enlarged, with the transverse sustaining-rod therein and a suspending-wire hooked over the rod. Fig. V is a perspective representation of one of the sustaining-rods and the end suspending-wires 25 in position thereon and removed from the other parts of the bed-bottom. Fig. VI represents the hook of one of the suspending-wires in position on the transverse sustaining-rod.

This invention relates to an improvement in 30 what are known as "re-enforced spring bed-bottoms"—that is, bed-bottoms which have their wire mattresses supported with coiled-wire springs—and the purpose is to attain the required yielding conditions for the under 35 spring-supports from the spring of a portion of the mattress of coiled wire. It has been the custom heretofore to support such mattresses by springs on cross-slats which are rigidly secured to the side rails, and to support them 40 by springs which are sustained by connecting-links attached to the same end rails to which the mattress is secured. The objection to the means for supporting these vertical coil-springs, as in the art shown, is the rigidity of 45 the bottom support, which really has no elasticity except that in the metal itself, or what little there may be in the middle of stiff transverse slats. I overcome this objection by two sustaining-wires, each being put edgewise 50 through the coiled woven-wire mattress far enough from the end rails to utilize a portion of the spring of the said mattress for the suspending-wires connecting said sustaining-wires.

A A represent the side rails, B the double end rails, and C the coiled woven-wire mattress, which compose what is known as the "suspended wire-mattress bed-bottom." To any of these mattresses I can apply my re-enforcing devices by means of sustaining-wires 60 d d, which are put transversely through the mattress parallel with and some little distance from the end rails, B, as shown, and in suspending-wires I, as many as may be required, hooked onto the transverse wires and made to 65 support the lower ends of hour-glass springs a a a by a direct connection therewith by means of links or staples, or support conical springs c c c by means of interposed transverse slats D D D, which are placed under each row 70 of springs and secured to them and to the wires I, by staples in the ordinary manner. The slats may, however, be connected by links, and two-part wires I be employed to connect them with the transverse wires d d. The 75 springs a a a may also be connected together by any well-known means, and wires I, running from each rod d, made to connect therewith by forming the ends of the wires into hooks m, 80 suitable to unite the parts.

It is proper to state that my devices can be attached to a woven-wire-mattress frame, where the woven wire has lost half of its original tension, and produce a first-class bed-bottom, inasmuch as supported or re-enforced mattresses 85 require less than half of the tensile strain that others do.

Having thus described my invention, what I claim, and desire to secure by Letters Patent of the United States, is—

In supported woven-wire-mattress spring bed-bottoms, the sustaining-rods d d, respectively put edgewise through the coiled woven-wire mattress, parallel to and some little distance from the end rails, B, so they will have a 95 movement to and from each other, as the weight on the mattress may be increased or diminished, and combined with suspending-wires I, the mattress-frame A B, and coil-springs supported by the wires I and placed under the 100 mattress C, substantially as specified, and for the purpose set forth.

CHARLES CARLETON.
